UNITED STATES PATENT OFFICE.

MINER E. FENNER, OF DURAND, ILLINOIS, ASSIGNOR OF ONE-HALF TO THOMAS L. HAMILTON,
OF DURAND, ILLINOIS.

CONCRETE CONSTRUCTION.

No. 901,798.

Specification of Letters Patent.

Patented Oct. 20, 1908.

Application filed January 20, 1908. Serial No. 411,672.

To all whom it may concern:

Be it known that I, MINER E. FENNER, a citizen of the United States, residing at Durand, in the county of Winnebago and 5 State of Illinois, have invented certain new and useful Improvements in Concrete Construction, of which the following is a specification.

The object of this invention is to construct 10 a wall of concrete blocks so that there will be vertically arranged air passage-ways adjacent to the outer face and adjacent to the inner face of the wall with horizontally arranged passage-ways connecting the vertically 15 arranged passage-ways.

The further object of this invention is to construct a building block with walls located at right angles to one another, and one of the walls being shorter than the other.

20 In the accompanying drawings, Figure 1 is an isometrical representation of a section of wall constructed of my improved blocks. Fig. 2 is a plan view of the wall. Fig. 3 is a transverse section and shown in perspective. Fig. 4 is a transverse section. Fig. 5 is a transverse section with the blocks separated a greater distance than in Fig. 4. Fig. 6 is a perspective view of the block.

My improved block comprises the vertically arranged wall 1, and horizontally arranged wall 2 located at right angles to one another, and of a proper thickness to give the necessary strength. The horizontally arranged wall 2 is shorter than the wall 1 and 35 the angle between the walls is filled in as at 3 to give greater strength. This block is made solid without openings in order to increase its strength.

At Figs. 1, 2, 3, 4 and 5 I have shown the 40 manner of laying a wall of my improved blocks, a half course is laid with the vertical walls forming the outer facing of the wall, another half course is laid with the vertical wall forming the inner face of the wall, the 45 horizontal walls of one course of blocks lying in contact. Another complete course is laid on the first course but the joints are broken half way between the joints of the first course. The third complete course is laid 50 over the second course with the joints broken half way between the joints of the second course, other courses are laid in the same manner. When the courses are thus laid,

there will be air passage-ways 4 extending the length of the wall adjacent to the inner faces of the vertical walls 1 of the blocks forming the outer face of the wall, and there will be other air-passage-ways 5 extending the length of the wall adjacent to the inner faces of the vertical walls of the blocks 60 forming the inner face of the wall.

When the blocks of a course are laid end to end as shown at Figs. 1 and 2, there is a central opening 6 formed by the cut away portion of the shortened horizontal walls 2. 65 This central opening forms a communication between two of the air passage-ways 4, at the outer face of the wall and two air passage-ways 5 at the inner face of the wall, and so on throughout the wall. The air 70 passage-ways adjacent to the outer face of the wall are on different horizontal planes than the air passage-ways adjacent to the inner face of the wall.

By forming the horizontal walls of the 75 blocks flat throughout their width, the blocks forming a given course may be separated more or less as shown at Fig. 5 in order that a wall of given or less thickness may be constructed.

Only one style of block is required to form the inner and outer faces of the wall.

I claim as my invention.

1. A building block comprising a facing wall and an interlocking projection, the projection being flush with one edge of the facing wall, and the front edge of the projection being shortened.

2. A building block comprising a facing wall and an interlocking projection, the 90 projection being flush with one edge of the facing wall, and the front edge of the projection being shortened at both ends.

3. A building block comprising a facing wall and an interlocking projection, the 95 projection being flush with one edge of the facing wall, and the front edge of the projection being shortened at both ends, and the angles at the ends being filled in.

In testimony whereof I have hereunto set 100 my hand in presence of two subscribing witnesses.

MINER E. FENNER.
